CLAIM

The ornamental design for an ice tray as shown and described.

DESCRIPTION

FIG. 1 is a front elevational view of an ice tray showing my new design, wherein the ice tray comprising an ice cube mold and a stick, is illustrated in an assembled configuration;

FIG. 2 is a rear elevational view thereof;

FIG. 3 is a left side view thereof;

FIG. 4 is a right side view thereof;

FIG. 5 is a top plan view thereof, wherein the stick is received in a groove on a top of the ice cube mold;

FIG. 6 is a bottom plan view thereof;

FIG. 7 is a top, front and left side perspective view thereof;

FIG. 8 is a top, front and left side perspective view showing the ice tray in a disassembled state, wherein the stick is disassembled from the ice cube mold;

FIG. 9 is a top, front and left side perspective view showing the ice tray in a state of use, wherein the stick is inserted into the ice cube mold; and,

FIG. 10 is a top, rear and left side perspective view showing the ice tray in the state of use, wherein the stick is inserted into the ice cube mold.

The broken lines in the drawings illustrate portions of the ice tray which form no part of the claimed design.
